MAGNETIC TAPE CARTRIDGE MAGAZINE

Rowland K. White, Montgomery County, Md., assignor to Qatron Corporation

Filed Mar. 5, 1970, Ser. No. 21,757

Term of patent 14 years

Int. Cl. D14—01

U.S. Cl. D26—14

FIG. 1

FIG.4

FIG. 1 is a top perspective view of a magnetic tape cartridge magazine showing my new design;

FIG. 2 is a side elevation view thereof, and is the same regardless of direction of view;

FIG. 3 is a top plan view thereof; and

FIG. 4 is a bottom plan view thereof.

I claim:

The ornamental design for a magnetic tape cartridge magazine, as shown and described.
